DEVICE FOR WORKING IN CERAMICS

Leonard Adams, Buffalo, N. Y.

Application June 27, 1951, Serial No. 233,715

17 Claims. (Cl. 25—22)

1

My device relates generally to the art of pottery, and in particular to that branch of the art known as ceramics.

The principal object of my invention is to provide a combination device which shall enable the ceramist to perform all of the various operations required in the forming of ceramics.

Another object is to provide a device of this nature having a potter's wheel and a variable speed drive mechanism for the wheel which are mounted in a case adapted to be supported in two positions at substantially right angles to each other, to facilitate some of the various operations possible with the device.

Another object is to provide a speed control for the device which may be operated either by foot or by hand.

A further object is to provide a device of this nature which is substantially self-contained and is portable so that it may be used at any desired place in, for instance, a home by a ceramist.

Moreover, my device is simple in design, durable in operation, and of such a nature that it may be easily and quickly adapted to the specific use of the ceramist.

The above objects and advantages have been accomplished by the device shown in the accompanying drawings, of which:

Fig. 1 is a side view of the device, partly in section;

Fig. 2 is a plan view of the same, also partly in section;

Fig. 3 is a fragmentary side sectional elevation showing the device set up for use as a lathe;

Fig. 4 is a plan view, partly broken away, of the arrangement shown in Fig. 3;

Fig. 5 is a fragmentary sectional elevation of my device set up and designed to be used as a jigger;

Fig. 6 is a plan view of the arrangement illustrated in Fig. 5;

Fig. 7 is a front face view of the device showing it as a slip mixer and also showing the device adapted to be controlled by means of the foot of the operator;

Fig. 8 is a plan view of the invention as shown in Fig. 7;

Fig. 9 is an enlarged plan view partly in section of the foot control means;

Fig. 10 is a side elevation of the foot control means;

Fig. 11 is an enlarged fragmentary sectional view taken on line XI—XI of Fig. 2; and,

Fig. 12 is a fragmentary sectional view of the foot control means and is taken on line XII—XII of Fig. 9.

2

My device comprises a casing 15, preferably of wood, which houses the power and speed control means. The casing is provided with two sets of feet 16, arranged on adjacent sides so that the casing may be placed in two positions at right angles to each other for most convenient location for performing various operations.

Arranged over the open top of the casing 15 is a top plate 20 having a peripheral flange 21 which is secured to the casing. The plate is also provided with a side wall 22 which is preferably inclined somewhat as shown in the drawings and which together with the bottom wall 17 forms a drainage trough 23. This trough is annular in form and extends from the side wall to a point below the periphery of the wheel 24. The central portion 25 of the top plate is raised above the bottom of the trough, whereby liquids being thrown from the wheel or being deposited in the top plate will be collected in the trough and conducted therefrom by means of a drainage pipe 26 (see Figs. 3 and 4) which is connected to a sump 30 formed at one side of the trough.

The wheel 24 is carried at the center of the top plate and is suitably mounted upon an anti-friction bearing 31, the inner race of which is secured to the wheel by means of a bearing ring 32, the outer race of the bearing being suitably mounted within the raised portion 25 of the top plate, as clearly shown in Fig. 1.

The power means for driving the wheel 24 is, for clearness of illustration, not shown in the drawings, but may be in the nature of a small electric motor suitably connected to a power transmission or torque converter 33. This torque converter is a standard article of manufacture, and will, therefore, not be described in detail. It is of the type which is controlled by the oscillation of its control shaft 34. The drive shaft 35 of the converter is arranged in coaxial relation with the wheel 24, and it is connected thereto by means of a two-part wheel shaft 40 having parts 41 and 48. These shaft parts are connected together by means of a clutch formed by a torque 45 and an engaging groove 46. The part 47 of the wheel shaft is mounted within a bore 41 formed in the bearing ring 32, and it is connected to the bearing ring and to the wheel by means of a pin 42 carried by the ring and disposed within a diametrically arranged slot 43 formed in the upper part 47 of the clutch wheel shaft. The shaft parts 41 and 48 are each formed with a clutch flange 44 and 50, respectively, between which is disposed the spaced arms 52 of a clutch cam yoke 51. These arms extend forwardly from a yoke 53 which has a control rod

54 attached thereto. The end of the control rod extends forwardly beyond the outer confines of the casing where it is provided with a control knob 74. From Fig. 1 it will be observed that the arms 52 of the clutch cam yoke are joined to the yoke 53 by means of cam surfaces 55 whereby the parts 47 and 48 of the shaft 46 may be separated by pushing the rod 54 inwardly, thereby causing the tongue 45 to be disengaged from the groove 46, and the wheel 24 thereby disconnected from the drive shaft 35 of the torque converter. A helical spring 49 is arranged between the bearing ring 32 and the flange 44 of the part 47 of the wheel shaft, whereby this part of the shaft will be urged downwardly so as to bring the tongue 45 thereof into engagement with the slot 46 of the shaft part 48 when in registering position and when the clutch cam yoke is moved to its inoperative position.

An opening 56 is provided at the front of the casing 15 over which a control plate 60 is mounted. This control plate is provided with a horizontally arranged slot 61 in which a control arm 62 is disposed. This arm consists of a sleeve 63 within which a control stud 64 is slidably mounted. The inner end of the control stud is attached to a torque control arm 65, which is connected to the control shaft 34 of the converter. A helical spring 66 is arranged between the leg 68 of the torque control arm 65 and the inner end of the control sleeve 63 to cause the sleeve to be urged outwardly upon the stud 64. A friction collar 70 is adjustably mounted upon the inner end of the control sleeve, and bears against the arcuate surfaces 71 of two spaced control flanges 67 which are carried by the control plate and are extended inwardly into the interior of the casing. The bearing surface of the collar is faced with suitable friction material. Under normal hand-control conditions, the helical spring 66 serves to press the friction collar against the inner faces of the control flanges, so as to increase the frictional contact and thereby retain the control arm in its adjusted position. A control knob 73 is preferably attached to the outer end of the control sleeve to facilitate its convenient operation.

The control plate has a handle lug 75 at each end thereof, and a handle 76 is pivotally attached thereto by means of pivot studs 80 which pass through the handle and into the lugs. These studs provide means for holding one end of the sleeve of a wire foot control, to be hereinafter described.

In Figs. 1, 2, 7, 9, and 11, the device is shown as arranged for manipulation by the foot of the operator, and the wire control from the foot control disc of Figs. 9 and 10 is shown as broken off but leading to the control plate of the device, as shown in Fig. 7. As here shown, the wire 82 of the control is attached to a wire stud 81 which engages registering apertures formed in the control sleeve 63 and in the control stud 64. As clearly shown in Figs. 1, 2, and 11, these apertures are in registration when the sleeve is pushed inwardly so as to disengage the friction collar 70 from the control flanges 67. When so engaged, the wire 82 of the wire control is passed through a registering aperture 83 formed in the wire stud, and in the control stud 64 and sleeve 63. In order to compensate for the angular movement of the control arm when it is being moved from one position to the other by means of the foot control, I provide a V-shaped slot 84 formed in each side of the stud 64 which merges

5 into the opening formed therein. The sleeve is also provided with a slot 85 through each side thereof at positions which register with the V-shaped slots 84 when the sleeve is pushed inwardly to its foot control position. The control wire is of the customary Bowden type which has a flexible sleeve or sheath 86 surrounding and slidably supporting the wire 82. As shown in Fig. 11, the outer end of the sleeve 86 is mounted within a recess 80 formed in the pivot stud 80 and it is secured in place by means of the set screw 91 positioned in handle lug 75 and the stud 80. Provision is made for the attachment of this end of the Bowden wire control at either side of the device, each of the pivot studs and adjacent handle lug being provided with a screw-threaded aperture for the reception of the set screw 91. After the sleeve and wire have been assembled, the wire 82 is fastened in position by means of a set screw 92 which passes into the bottom of the wire stud 81 and is brought to bear against the wire mounted in the aperture of the stud. When the device is set up for the foot control, it will be obvious that the friction collar 70 will be spaced from the control flanges, and that the control of the arm 62 will be under the influence of the foot control mechanism.

The foot control mechanism comprises a base 93 which is provided preferably with rubber feet 94 so as to prevent its slipping when being operated. The control disc 95 is rotatably mounted upon the base 93 and is preferably fitted into an annular recess 96 formed in the base. The disc is provided with an annular groove 97 for the reception of the wire 82 of the control. The base is also formed with an aperture 100 extending across from one side thereof to the other and is located tangentially with respect to the groove 96. The aperture 100 is provided at each of its outer ends with a counterbore 101 for the reception of the outer end of the sleeve 86 of the control. A set screw 102, engageable with either aperture 103 formed in the base, serves to clamp the sleeve 86 in position. The adjacent end of the wire 82 is preferably formed with an inturned end 104 which engages with a radial aperture 105 formed in the disc and in registration with the groove 97. The disc is formed on its upper surface with a number of radiating vanes 106 to receive the foot of the operator in substantially non-slipping manner. Obviously, when the disc is to be actuated the operator twists his foot in either direction to bring about the desired speed of the wheel.

An electric switch 110 is carried by the control plate at a position preferably underneath the control arm, and this is suitably connected in well known manner to the control motor of the device (not shown) and to a suitable source of electric energy.

The flange 21 of the top plate 20 is provided at each corner with a screwthreaded aperture 112 for the reception of one of a number of posts 113. These posts, are shown in Figs. 3, 5 and 7, extend a suitable distance above the flange of the plate and serve to support various parts of the machine while being used. A yoke 114 serves to connect three of the posts when they are attached to the flange, and this yoke comprises three yoke arms 115, a yoke head 116 at the end of each of the arms, and a yoke hub 120 at the center thereof. Each of the yoke heads 116 is formed with a slot 121 and a clamping bolt 122 is passed through the slotted portion, whereby each of the yoke heads may be securely clamped in

5

position upon the engaged post. A clamping screw 123 is carried by the yoke head for clamping a number of the parts of the device in operative position.

In order that the ceramist may use the device for accomplishing various steps and functions in his art, I provide a number of components which form parts of the complete combination. For instance in Fig. 5, I show the device arranged to perform a jiggering operation and two posts 113 are used. If desired, the yoke 114 and the three posts may be used. As here shown, a tool supporting bar 125 is provided, one end thereof being pivotally mounted in a pivot block 126 whereas the other end is supported within a slot 130 formed in a stop block 131. The bar carries a jigger blade 132 which is held in place by means of a jigger clamp 133. The pottery being formed by the jigger is shown at 134. The pivot block 126 and stop block 131 are each mounted upon one of the posts 113, which, for these operations, are arranged diametrically opposite each other. So as to be able to accurately determine the position of the jigger tool when the workpiece is finished, I provide a stop screw 135 which is carried by the stop block 131 and which limits the downward movement of the pivotally mounted tool supporting bar 125. The bar is provided at its outer end with a hook 136, which may be brought into engagement with the adjacent post 113 to hold the bar in its inactive position, as shown in dotted lines in Fig. 5, thereby giving unhampered access to the table. Each of these blocks is provided with a slot 137 which merges into the bore 140, and a clamping screw 141 passes through the slotted portion of each, whereby they may be clamped to the engaged posts at any desired position.

When the ceramist desires to use the device as a lathe and to produce an object similar to that shown in Fig. 3, all three of the posts 113 are used together with the yoke 114. When the device is to be used in this manner, the pivot block 126 and the stop block 131 are engaged with two of the posts on the same side of the device, as clearly shown in Fig. 4. The tool supporting bar 125 is then clamped to the side faces of these blocks by means of clamping screws 141 and wing nuts 142.

When the lathe of my device is to be used, a tool rest 143 is provided which is carried by the supporting bar 125 and which comprises a tool rest block 144 suitably clamped in desired position to the supporting bar. A tool rest post 145, which is preferably a part of the tool block, carries a tool rest 146 and a clamp screw 150 for securing the tool rest in desired position. For this operation a dead center 151 is employed to support the outer end of the workpiece or the core 152 carried by it. This dead center is carried by a rod 153 which is passed through the yoke head 120 and is secured in place by means of the screw 123. While this operation may, if desired, be performed with the workpiece in a vertical axial position, it may in some cases be preferable to operate upon the workpiece with its axis in a horizontal plane. To this end the casing may be turned through 90° and the wheel 24 supported on its horizontal axis. The screws 141 of the stop block and pivot block are extended beyond the blocks so that when the casing is in this horizontal position, these screws will rest upon the supporting surface (not shown) and thereby steady the outer projecting end of the device.

In order to provide means whereby the ceramist

6

may mix his slip to a liquid consistency, I provide, in the periphery of the wheel 24, a number of radially arranged apertures 154 for the reception of the lower inwardly bent ends 155 of a number of rods 156. These rods are extended upwardly and pass through suitable clamping means 160 which are engaged with the upper edge 161 of a container 162. The upper ends of the rods are screwthreaded and provided with wing nuts 164. The slip to be mixed is placed within the container, and the rod 153 is secured in the yoke head 120 and is extended well into the container where a paddle 163 is disposed. The paddle 163 is nonrotatably secured to the lower end of the rod 153, and it may be disposed in any desired position within the container and secured in such position by having the rod 153 clamped within the head 120 of the yoke by means of the clamp screw 123.

From the foregoing, it will be obvious that when the potter's wheel is to be used, the control knob 74 is pulled out to connect the torque converter to the wheel shaft and the desired speed of the wheel is controlled by adjustment of the control lever 62. Should, however, it be desired to use both hands to manipulate the material being fashioned, the foot control means, illustrated in Fig. 9, are employed. It should be noted that for convenience of illustration, the control lever is shown in its middle position, and it is obvious, that this lever is movable from one end of the slot 61 to the other in adjusting the speed of the wheel.

When the device is set up for foot operation and it is desired to actuate it by hand, the wire control 82 is disconnected from the control plate by loosening the set screws 91 and 92 and by removing the control wire with its sleeve, after which the wire stud 81 is removed from the registering apertures in the sleeve 63 and stud 64. This will permit the helical spring 66 to push the sleeve outwardly so as to bring the friction collar 70 into engagement with the faces of the control flanges 71 which will cause the control arm to be retained in any of its adjusted positions.

When it is desired to stop the rotation of the wheel for any purpose whatever, it is not necessary to interrupt the rotation of the motor and torque converter, since the control rod 54 may be pushed inwardly to disconnect the clutch and allow the drive shaft to rotate freely without actuating the wheel 24. When it is again desired to cause the wheel to rotate, it is only necessary to pull outwardly on the control knob 74 which will bring the clutch cam yoke to its inoperative position and permit the engagement of the clutch.

When the ceramist desires to mix glaze, the device may be used as a ball mill. When so used, the receptacle 162 may be clamped to the wheel as herein described and as shown in Fig. 7. Obviously, the paddle 163 and rod 153 are not used for this operation and the top of the container is provided with a cover (not shown). The device is then placed upon its side and the container rotated to grind the material in well known manner.

My device is so compact and the materials which are being handled are so controlled and restricted to their zones of operation that the whole device may be used at any desired and convenient place, for instance, the ceramist may take the device into a living room and there perform all of the operations desired without fear of disturbing the surroundings or the soiling of floor coverings or furniture.

What I claim is:

1. A device for working in ceramics comprising a casing, a stationary top plate mounted upon the casing, a potter's wheel rotatably supported by the top plate, a variable speed torque converter mounted within the casing and having a drive shaft and a separate control shaft, a reciprocating shaft for the wheel, a clutch associated with the wheel shaft, means for actuating the clutch to connect and disconnect the wheel to and from the converter, means connected to the control shaft for controlling the speed of the converter, the top plate having a number of equidistantly spaced threaded apertures, a number of posts engageable with the threaded apertures for extension in a direction normal to the top plate, and means carried by the posts for attaching various working tools thereto.

2. A device for working in ceramics comprising a casing, a stationary top plate mounted upon the casing, a potter's wheel rotatably supported by the top plate, the top plate having a number of equidistantly spaced threaded apertures arranged symmetrically around the axis of the wheel, a number of posts engageable with the threaded apertures in variable arrangement for extension in a direction normal to the top plate, and stationary attachment blocks adjustably carried by the posts and adapted to support various tools for operation upon workpieces carried by the wheel.

3. A device for working in ceramics comprising a casing, a top plate mounted upon the casing, a potter's wheel rotatably supported by the top plate, a torque converter mounted in the casing and having a drive shaft and a separate control shaft, a two-part wheel shaft connecting the wheel with the converter drive shaft, a control plate carried by the casing and having an elongated slot, and a control lever mounted in the slot of the plate and having its inner end connected to the control shaft for oscillating the same.

4. A device for working in ceramics comprising a casing, a top plate mounted upon the casing, a potter's wheel rotatably supported by the top plate, a torque converter mounted in the casing and having a drive shaft and a separate control shaft, a two-part wheel shaft connecting the wheel with the converter drive shaft, a control plate carried by the casing and having an elongated slot, arc-shaped control flanges carried by the plate and arranged one on each side of the slot, a control lever mounted within the slot of the plate and having a stud member connected at its inner end to the control shaft of the converter, a sleeve member slidably mounted upon the stud member, a friction collar carried by the sleeve and engageable with the arcuate surfaces of the control flanges, and resilient means for pressing the friction collar into contact with the flanges.

5. A device for working in ceramics comprising a casing, a top plate mounted upon the casing, a potter's wheel rotatably supported by the top plate, a torque converter mounted in the casing and having a drive shaft and a control shaft, a wheel shaft connecting the wheel with the converter drive shaft, a control plate carried by the casing and having an elongated slot, arc-shaped control flanges carried by the plate and arranged one on each side of the slot thereof, a control lever mounted within the slot of the plate and having a stud member connected at its inner end to the control shaft of the converter, a sleeve

member slidably mounted upon the stud member, a friction collar carried by the sleeve and engageable with the arcuate surfaces of the control flanges, resilient means for pressing the friction collar into contact with the flanges, the control stud and control sleeve each being formed with registerable apertures, and a wire stud for pivotal engagement with the apertures when in registering positions, the apertures in the control stud and control sleeve being so positioned that when engaged by the wire stud, the friction collar will be out of contact with the control flanges.

6. A device for working in ceramics comprising a casing, a top plate mounted upon the casing, a potter's wheel rotatably supported by the top plate, the top plate being formed with a side wall and an annular drainage trough surrounding the wheel, the top plate having a number of equidistantly spaced threaded apertures arranged symmetrically around the axis of the wheel, a number of posts engageable with the threaded apertures in variable arrangement for extension in a direction normal to the top plate, a yoke having a hub for the attachment of a supporting rod, the yoke being formed with radiating arms each having a slotted head for clamping component parts of the device to the posts, and means carried by the posts for attaching various working tools thereto.

7. A device for working in ceramics comprising a casing, a top plate mounted upon the casing, a potter's wheel rotatably supported by the top plate, a torque converter mounted in the casing and having a drive shaft, a two-part wheel shaft connecting the wheel with the converter drive shaft, each part of the wheel shaft being provided near its end with a coacting clutch part, spaced cam arms formed on said yoke and disposed between the clutch flanges, and cam means formed on the arms for engagement with the collars to cause the clutch parts to be engaged and disengaged.

8. A device for working in ceramics comprising a casing, a top plate mounted upon the casing, a potter's wheel rotatably supported by the top plate, a torque converter mounted in the casing and having a drive shaft and a control shaft, a wheel shaft connecting the wheel with the converter drive shaft, a control plate carried by the casing and having an elongated slot, arc-shaped control flanges carried by the plate and arranged one on each side of the slot thereof, a control lever mounted within the slot of the plate and having its inner end connected to the control shaft, a foot control formed with a rotatable disc, and a push-pull wire engageable with the control lever at one end and having its other end disposed within an annular groove formed in the disc, whereby the control lever may be actuated by rotation of the disc by the foot of the operator.

9. A device for working in ceramics comprising a casing, a top plate mounted upon the casing, a potter's wheel rotatably supported by the top plate, a torque converter mounted in the casing and having a drive shaft and a control shaft, a two-part wheel shaft connecting the wheel with the converter drive shaft, a control plate carried by the casing and having an elongated slot, a control lever mounted within the slot of the plate and having its inner end connected to the control shaft of the converter, and foot controlled means for actuating the control lever, comprising a base, a rotatable disc carried thereby, and flexible control means connecting the base and

the disc with the control plate and the control lever, respectively, whereby the lever may be actuated by a twisting movement of the foot of the operator.

10. A device for working in ceramics comprising a casing, a stationary top plate mounted upon the casing, a potter's wheel rotatably supported by the top plate, the top plate having three triangularly positioned threaded apertures, three posts engageable with the threaded apertures for extension in a direction normal to the top plate, and stationary attachment blocks adjustably carried by the posts for securing various working tools thereto.

11. A device for working in ceramics comprising a casing, a stationary top plate mounted upon the casing, a potter's wheel rotatably supported by the top plate, a variable speed torque converter mounted within the casing and having a drive shaft and a separate control shaft, a two-part wheel shaft for connecting the wheel to the drive shaft, a clutch associated with the wheel shaft and formed between the parts thereof, means for actuating the clutch to connect and disconnect the wheel to and from the drive shaft of the converter, and means connected to the control shaft for controlling the speed of the converter.

12. A device for working in ceramics comprising a casing, a stationary top plate mounted upon the casing, a potter's wheel rotatably supported by the top plate, a variable speed torque converter mounted within the casing and having a drive shaft and a separate control shaft, a two-part wheel shaft, one part of the wheel shaft being reciprocally mounted, a clutch mounted between the parts of the wheel shaft, cam means disposed between the adjacent ends of the wheel shaft parts for actuating the clutch to connect and disconnect the wheel to and from the converter, and means connected to the control shaft for controlling the speed of the converter.

13. A device for working in ceramics comprising a casing, a stationary top plate mounted upon the casing, a potter's wheel rotatably supported by the top plate, a torque converter mounted in the casing and having a drive shaft and a separate control shaft, a two-part wheel shaft connecting the wheel with the converter drive shaft, a clutch cam yoke having spaced cam arms disposed between the adjacent end of the wheel shaft for connecting and disconnecting the parts of the latter, and means connecting to the control shaft for controlling the speed of the wheel.

14. A device for working in ceramics comprising a casing, a stationary top plate mounted upon the casing, a potter's wheel rotatably supported by the top plate, a torque converter mounted in the casing and having a drive shaft, a two-part wheel shaft connecting the wheel with

the converter drive shaft, one part of the wheel shaft being secured to the drive shaft, the other part of the wheel shaft being slidable within the hub of the wheel and having a diametrically arranged slot in its upper end, a stationary diametrically arranged pin carried by the hub of the wheel and slidably engaged with the slot formed in said other part of the wheel shaft, the adjacent ends of the wheel drive shaft parts being formed with coating clutch surfaces, and means for engaging and disengaging the clutch surfaces.

15. A device for working in ceramics comprising a casing, a stationary top plate mounted upon the casing, a potter's wheel rotatably supported by the top plate, the top plate being formed with a side wall and an annular drainage trough, the top plate having three triangularly positioned threaded apertures equidistantly spaced from the axis of the wheel, a number of posts engageable with the threaded apertures for extension in a direction normal to the top plate, and adjustable attachment blocks carried by the posts for securing various working tools thereto.

20 16. A device for working in ceramics comprising a casing, a stationary top plate mounted upon the casing, a potter's wheel rotatably supported by the top plate, the top plate having a number of threaded apertures equidistantly spaced from the axis of the wheel, a number of posts engageable with the threaded apertures for extension in a direction normal to the top plate, stationary attaching blocks adjustably carried by the posts, and a tool supporting bar secured to the blocks, 25 and forming tools carried by the bar.

30 17. A device for working in ceramics comprising a casing, a top plate mounted upon the casing, a potter's wheel rotatably supported by the top plate, a torque converter mounted in the casing and having a drive shaft and a control shaft, a wheel shaft connecting the wheel with the converter drive shaft, a control plate carried by the casing and having an elongated slot, a control lever mounted within the slot of the plate and having its inner end connected to the control 35 shaft, a foot control formed with a rotatable disc, and a push-pull wire engageable with the control lever at one end and having its other end disposed within an annular groove formed in the disc, whereby the control lever may be actuated by rotation of the disc by the foot of the operator.
